ARTIFICIAL LIMB

Isaac Touson, Buenos Aires, Argentina

Application October 28, 1949, Serial No. 124,201
In Argentina August 31, 1949

6 Claims. (Cl. 3-2)

1

The present invention relates to artificial legs for use by persons who have had amputations above the knee.

It is a principal object of the present invention to provide a knee-joint which, while it shall enable the amputee to move at will, the mere movement of the stump or the body, the two parts of the leg from a straight position to different angular positions, shall always afford a positive locking of the parts which shall impede further bending or collapse of the joint in response to the weight of the body, thereby preventing falls or loss of equilibrium.

A further object is to provide a knee-joint which shall enable the leg to be bent to a given angle at will and to be then subjected to the load of the wearer person without danger that it continue to bend, and for the return to the straight position, shall require only to be lifted by a simple movement of the stump or by inclination of the body together with the transfer to the other leg of the weight of the body.

A further object is to provide a knee-joint which shall enable the wearer readily and reliably to perform the movements of walking and even going up and down stairs, sitting down and other similar actions, within the range of the natural member.

Another of the objects of the invention is to provide an artificial leg comprising a knee joint having structural features including cooperating convex and concave substantially parabolic surfaces which enable the shin portion to perform or simulate the movements of the human leg in a highly natural manner.

Another object is to provide a leg including a knee joint comprising a main connection of the shin portion with the thigh portion which will permit coordinated relative movements at the knee, and auxiliary connection means for connecting the thigh portion and the shin portion in such a manner that the shin portion is automatically and resiliently urged to straight leg position with reference to the thigh portion.

With the above and other objects in view, which will more readily appear as the nature of the invention is better understood, the same consists in the features shown in the accompanying drawings in which:

Figure 1 is a side elevation of the improved artificial leg with the lower unit shown partly in section;

Figure 2 is a rear elevation, partly in section, of the leg of Figure 1;

Figure 3 is a horizontal sectional view taken on the line 3-3 of Figure 2;

2

Figure 4 is a horizontal sectional view taken on the line 4-4 of Figure 2;

Figure 5 is a horizontal sectional view taken on the line 5-5 of Figure 2;

Figure 6 is a detail elevation of the automatic actuating device for impelling the two units composing the leg into the normal upright position;

Figure 7 is a side elevation on a reduced scale of the two units composing the leg, in both a vertical and an angular position, respectively;

Figure 8 is a perspective view of the lining which guides the movement of the transverse pin joining the two units in the region of rotular connection;

Figure 9 is a fragmentary detail showing the connection between the transverse pin and the flexible lining;

Figure 10 is a detail sectional view along line 10-10 of Figure 9;

Figure 11 is a fragmentary side elevation partly in section, of the structure shown in Figure 10.

Similar numerals and reference characters denote the same or corresponding parts in the several views.

In accordance with the accompanying drawings, the improved artificial leg comprises an upper or thigh unit *a* and a lower foreleg section or peroneotibial unit *b*. The latter is secured by its lower end to the complementary unit *c*, consisting of the foot.

The upper unit *a* has, at its lower end, a substantially parabolic wall surface 1 constituting the area of sliding contact with the concave parabolic wall surface 2 at the upper or socket end of the lower unit *b*. Interposed between these surfaces are the yielding frictional contact members which will hereinafter be described more in detail.

The units *a* and *b* are articulated by a knee bolt arrangement hereinafter described operating in conjunction with automatic stabilizer or control means 6-12 and 23 and 24, and a guiding transverse pin and slot arrangement. First, it

will be seen that the upper unit *a* is provided with a transverse pin 3 connected with the lateral ears 4 of the lower unit *b*, said pin being movable within slot 5 provided in the lower part or knee portion of the upper unit *a*.

As previously indicated, the improvements herein consist in an arrangement for automatically urging the two units *a* and *b* into the normal upright position corresponding to the vertical position of the user on the ground when standing still, as shown in Figure 1. Said arrangement comprises an elongated hollow mem-

ber

ber 6 anchored to the lower unit b by pivot 7 fastened to a forked bracket 8 (Figs. 1 and 5) with interposition of a ball bearing race 9 (Fig. 6) occupying a cavity provided in the widened end 10 of elongated member 6. Bracket 8 has its web 39 secured to the inner rear part of unit b by fastenings 38 not far from foot c while its arms 34 support the pivot 7.

The elongated member 6 has an axial bore or cavity 11 which receives the lower part of a solid control rod 12, a helicoidal spring 13 (Fig. 1) being interposed between that end of the rod which enters cavity 11 and the bottom of said cavity. The upper end of rod 12 extends into the thigh unit a through a slot 14 (Fig. 2) and terminates in an eye 15. This eye receives a ball bearing race 16 whose inner shell is supported on a stud 17 (Fig. 3) received within the bushings 19 having integral flanges 19a for firmly abutting against the sides of the eye 15. The reduced ends of the bushings are in the nature of bolts 20 which are secured in opposite sides of the thigh unit a.

Rotatably mounted on the ends of a transverse shaft 21 of rod 12 near the concave parabolic surface 2 of unit b, said rod 12 carries two rollers 23 guided in rails 24 secured to the inner face of surface 2, the said rollers, in cooperation with the rails, constituting means for compelling the movement of rod 12 forward or backward, without lateral displacements.

Transverse pin 3 is guided in a lining 25 of flexible material provided in slot 5 of the upper unit a. The length of the lining corresponds to that of slot 5 and silences the sliding movement of the transverse pin in an efficient manner.

The transverse pin has at its opposite end a stud 26 onto which a nut is screwed, the said stud being engaged by a roller bearing assembly 27 mounted in ear 4 of unit b, as shown in Figure 10. Retention nuts 28 secure the said studs on either side of the upper unit a. The inter-position of roller bearing imparts greater sensitivity to the rotary movement of the pins, thus facilitating the angular motions of both units a and b in accordance with the motions of the user.

The lower widened end 10 of the elongated member 6 ends in a radial cam portion 29 against the free end of which bears the end of a laminar spring 30 (Figs. 1 and 7). Said spring 30 and helicoidal spring 13 cooperating therewith constitute the elastic means for urging the two units a and b into the normal position shown in Figure 1 by means of members 6 and 12, upon which said springs act in the directions indicated by the arrows F for spring 13, and F' for spring 30, respectively.

As an alternative for the cam 29 and spring 30, or in supplement thereto as shown in Figure 1, the lower section 6 of the telescopically engaged parts 6 and 12 may be tensioned in the direction of the arrows F' by a resilient loop x anchored about the part 6 and connected with a screw y which in turn is engaged by the internally threaded portion z of a sleeve z' of a control nut z'', so that by operating the nut, the screw y will be moved in the direction of its axis to impose more or less tension on the loop x.

To the concave parabolic upper face 2 of the lower unit b there is secured a flexible laminar member 31. In frictional contact therewith is a lining 32 of shorter length provided in the rear part of the convex parabolic end 2 of the upper unit a. These two laminar elastic members 31

and 32 form surfaces of yielding, constant contact in any of the positions into which the units a and b may be urged under the load of the body indicated in Figure 11 by the arrows F'.

5 Bearing all of these hereinabove described structural features in mind, the operation of the artificial leg according to the present invention will be readily understood.

Starting from the straight position of the leg 10 when worn by an amputee, the resilient inserts 32 will be pressed down against the concave surface 2 of 31 and concave closure member 36, and, since said inserts 32 yield a little under compression, will thus cause a load to be imposed substantially axially on connection member 6, thereby pushing rod 12 slightly into tubular member 11 and compressing spring 13 and depressing the rollers 23. When it is desired to bend the knee as in mounting a stair, the wearer's weight is first transferred from the artificial leg to the other so that the load is removed from the connecting member 6 and spring 13 expands to raise the rod member 12 thereby slightly lifting the rear part of the thigh portion a so as to prepare same for easier swinging, and also bringing the rollers 23 into engagement with the exposed surfaces 42 of rails 24 to prevent the rearward part of the end of the thigh portion a from being lifted out of the aforesaid trough-like cavity.

As the artificial knee is bent as hereinbefore described, the resilient inserts 32 move forward over concave surface 2 and the pin 17 will also move forward and also downward towards said surface 2 thereby causing connecting member 6 to swing around lower pin 7 and the rod member 12 to be pushed into the tubular member 11 thereby compressing spring 13 and causing rollers 23 to be retracted from the rails 24, and at the same time the cam projection 29 will depress the leaf spring 30, and the loop x will be tensioned as hereinabove described.

The compressed and depressed springs and tensioned loop will not however, be effective to prevent bending of the knee or to assist in returning the leg to the straight position so long as there is a load upon the leg as hereinabove made clear. As soon as the load is relieved, as by the commencement of a straightening movement, 45 the leaf spring 30 and the loop x will apply forces to the connection member 6 to restore same to its normal position and the coil spring 13 will exert an upward thrust on rod 12 tending to lift the rear part of the end of the thigh portion a, so as to keep the resilient inserts 32 floating over the surface 2 and thus prevent accidental jamming, while the rollers 23 will gradually be brought closer to the rails 24 which they engage towards the end of the return stroke.

60 I claim:

1. An artificial limb, comprising, a thigh unit including a knee-portion having curved slots in its opposite side walls and a vertical slot in its rear wall, a foreleg unit including a knee-portion receiving socket, mating arcuate wall portions at the knee-portion and socket portions of said units, a transverse pin carried by the foreleg section and guided in said slots, a knee-bolt transversely mounted in the rear of the knee-portion of the thigh unit, and automatic means for urging the thigh and foreleg units into vertical alignment, said means comprising solid and hollow members telescopically connected at their inner ends, means for connecting the outer end 65 of said solid member to the knee-bolt, and pivot 70 means for urging the thigh and foreleg units into vertical alignment, said means comprising solid and hollow members telescopically connected at their inner ends, means for connecting the outer end 75 of said solid member to the knee-bolt, and pivot

and bracket means for connecting the outer end of the hollow member to the inner wall of the foreleg unit, parallel track members on the wall of the socket portion of the foreleg member, guide rollers on the said solid member for engaging said track members, and means for exerting a yielding lateral force on said telescopically related solid and hollow members.

2. An artificial limb according to claim 1, wherein, the curved slots in the knee-portion of the thigh unit are provided with resilient linings.

3. An artificial limb according to claim 1, wherein, the means for exerting a yielding lateral force on said telescopically related solid and hollow members comprises a cam offset from the end of the hollow member and a leaf spring carried by the bracket and engaging said cam.

4. An artificial limb, comprising, a thigh unit including a knee portion having arcuate slots in its opposite sides and also having an arcuate bearing wall, a foreleg section having an arcuate bearing wall including spaced strips having guides on their lower faces, a transverse pin carried by the foreleg section and guided in said arcuate slots, a control rod pivoted at one end in the thigh unit and extending into the foreleg unit, rollers on the control rod engaging in said guides, and yielding means cooperating with said control rod to urge it in a direction to force the thigh and foreleg units in vertical alignment.

5. An artificial limb, comprising, a thigh unit and a foreleg unit having arcuate mating knee portions, a knee bolt in the thigh unit, and control means tending to keep the units in vertical alignment.

alignment and including a pair of telescopic members, one of said members being pivotally supported at its upper end by the knee bolt and extending into the foreleg unit and having a resilient connection therewith, guide means on the arcuate knee portion of the foreleg unit, rollers carried by said last mentioned member and bearing in said guide means, and the other of said members being pivotally connected to a bracket in the foreleg unit.

5 10 15 20 25 30 35

6. An artificial limb, comprising, a thigh unit and a foreleg unit having arcuate mating knee portions, a knee bolt in the thigh unit, control means carried by said bolt and extending into the foreleg unit and having a resilient connection therewith comprising a resilient loop anchored to the control means, tensioning means for said resilient connection and comprising a screw connected with the loop, and a rotatable nut held in the foreleg unit against axial movement and engaging the screw.
